UNITED STATES PATENT OFFICE.

MAX F. STADTMULLER, OF PIERRE, SOUTH DAKOTA.

DOOR-FASTENER.

979,218.

Specification of Letters Patent. Patented Dec. 20, 1910.

Application filed June 4, 1910. Serial No. 565,101.

To all whom it may concern:

Be it known that I, MAX F. STADTMULLER, citizen of the United States, residing at Pierre, in the county of Hughes and State 5 of South Dakota, have invented certain new and useful Improvements in Door-Fasteners, of which the following is a specification.

This invention relates to new and useful improvements in locks and latches, and relates particularly to fasteners for car doors.

The invention has for its primary object a simple, durable and efficient construction of car door fastener, the parts of which may be easily manufactured and readily assembled and applied to a car, and which in operation will prove serviceable and effective in holding the lower edge of the door from swinging outwardly as well as prevent the entire door from moving laterally when the 20 door has been moved to a closed position over the doorway.

With this and other objects in view as will more fully appear as the description proceeds, the invention consists in certain 25 constructions, arrangements and combinations of the parts that I shall hereafter fully describe and claim.

For a full understanding of the invention reference is to be had to the following description and accompanying drawings, in which:—

Figure 1 is a perspective view of a car door embodying my improved latch mechanism. Fig. 2 is a front elevation of the 35 device with the door open. Fig. 3 is a similar view with the door closed and locked, and Fig. 4 is a detail sectional view on the line 4—4 of Fig. 3.

Corresponding and like parts are referred 40 to in the following description and indicated in all the views of the drawings by the same reference characters.

Referring to the drawings the letter A designates the portion of a freight car provided with the usual doorway *a*, and 1 designates a suspension rail which extends over the door-way and to one side thereof in the usual manner.

Hangers 2 are provided with rollers 3 by 50 which they are mounted to ride along the suspension rail 1, said hangers being secured

in any desired way to the door 4 which may be of any desired construction or formation, and of course, of a size to close the doorway *a* when the door is moved in one direction along the suspension rail 1. The door 4 is limited in its movement in one direction by a stop-strip 5 which is in the present instance of angle metal extending vertically, as shown, and secured to one side of the 60 door-way, one flange, or member of the strip projecting perpendicularly from the door-frame as clearly illustrated in the drawings.

In order to hold the door from swinging outwardly at its lower edge from the doorway *a*, I have provided a horizontally extending rod 6 which is journaled in bearing brackets 7 that are secured to the side of the car underneath the door sill, as shown, said rod being mounted to turn, or partially rotate about its longitudinal axis, and fingers 8 are projected substantially perpendicularly from the rod 6 at the ends thereof, as shown, the fingers being secured to the rod in any desired way, or formed integral therewith, as desired. When the rod is turned in one direction, the fingers will engage the lower edge of the door at the outer face thereof and securely hold the door from swinging outwardly away from the 80 door-way. Preferably, the door is provided at its lower edge with a wear-strip 9, with which the fingers 8 directly engage near one side edge of the door. The latter is provided with a keeper lug 10 designed for engagement by one of the fingers 8, whereby to not only hold the door from swinging outwardly but from accidentally moving laterally to an open position after it has once been closed and the fastening devices 90 operated.

In order to operate the rod 6, the same is provided at one end with a pinion 11 which meshes with a vertically disposed rack 12, the rack being mounted for a vertical movement in a guide channel 13 which is formed in the adjoining bearing bracket 7. The upper end of the rack 12 is pivotally connected to the lower end of a link-rod 14, and the upper end of the link-rod is in turn 100 pivotally connected to an operating lever 15 which is fulcrumed at one end on a stud

16, as shown. The lever 15 is provided with an operating handle 17 and with a hooked lug 18, the latter being designed to move in between apertured ears 19 that are formed on a plate 20 secured to the side of the car contiguous to one edge of the doorway. A bolt 21 is mounted for a longitudinal movement in the apertured ears 19 and the plate 20 and is designed to be slipped down back of the hooked lug 18 so as to lock the bolt 21 in a closed position.

From the foregoing description in connection with the accompanying drawings, the operation of my improved car door fastener will be apparent.

In the practical use of the device, after the car door has been moved to closed position, the operating lever 15 may be grasped by the operator and swung downwardly and inwardly toward the door-way in a plane parallel to the plane of the door-way, this movement of the lever, through the instrumentality of the link-rod 14 and rack and pinion, turning the rod 6 in a direction to carry the fingers 8 upwardly and inwardly into engagement with the wear-plate 9 at the lower edge of the door, and one of said fingers into engagement with the keeper lug 10, the door being thereby held not only from swinging outwardly at its lower edge but from any accidental movement along the suspension rail 1 toward the open position. After the parts have been thus manipulated, the bolt 21 will be slipped down back of the hooked lug 18, thereby securely locking the operating lever.

It is to be particularly noted that my invention provides a car door, which is permitted to swing out freely as soon as the latches have been retracted, thereby leaving the door free to be opened, as the door can easily pass any obstruction which it could not do if it were connected to the car (as is the case with the ordinary car doors) at both top and bottom edges. To those versed in the art to which this invention appertains, it is well known that considerable difficulty is at all times experienced in opening car doors owing to the fact that the door meets with some obstruction which it cannot pass as it is compelled to move in a definite plane. Obviously my invention precludes the liability of sticking, as the door can freely swing out after it has once been unlocked.

While my invention has herein been described as a car door fastener, it is of course to be understood that the invention is equally applicable for use in connection with other doors, and that various changes may be made in the construction, arrangements and proportions of the parts without departing from the scope of the invention as defined in the appended claims. It is also to be understood that the term "car" in the claims is not to be construed in its limited

sense, but should be considered as including any part provided with a door-way and a door designed to close the same.

Having thus described the invention what is claimed as new is:—

1. The combination with a car provided with a door-way, of a door arranged to be moved across the door-way and suspended so as to swing outwardly therefrom at its lower edge, a rod journaled on the car and provided with a finger engageable with the door to prevent its lower edge from moving outwardly and the door as a whole from moving away from the door-way in a plane parallel to the plane of the door-way and means for turning said rod.

2. The combination with a car provided with a door-way, of a door arranged to be moved across the door-way and suspended from its upper edge, a rod journaled on the car to partially rotate about its longitudinal axis, and provided with a finger adapted to engage the lower edge of the door to prevent it from swinging outwardly, and means for operating said rod, the door being provided with a keeper lug for engagement by said finger whereby to prevent the door from moving away from the door-way in a plane parallel to the plane thereof.

3. The combination with a car provided with a door-way, of a sliding door adapted to move across the door-way, a rod journaled on the car and provided with means for engaging the door to prevent it from moving away from the door-way, a pinion secured to said rod, a rack meshing with said pinion, and means for operating the rack whereby to turn the rod.

4. The combination with a car provided with a door-way, the door adapted to move across the door-way, a rod journaled on the car and provided with a finger arranged to engage the door to prevent it from moving away from the door-way, a pinion secured to the rod, a rack meshing with said pinion, an operating lever fulcrumed on the car, and a link connection between the lever and the rack.

5. The combination with a car provided with a door-way, a door adapted to move across the door-way, a rod journaled on the car and provided with means for engagement with the door to prevent it from moving away from the door-way, a pinion secured to the rod, a rack meshing with said pinion, a support for the rack, a lever fulcrumed on the car and operatively connected with the rack, the lever being provided with a lug, and a bolt carried by the car and arranged to engage the lug whereby to hold the bolt in one position.

6. The combination with a car provided with a door-way, of a door adapted to move across the door-way, a rod, brackets in which said rod is journaled to partially ro-

tate about its longitudinal axis, a finger carried by the rod and arranged to engage the door to prevent it from moving away from the door-way, a pinion secured to the door, 5 a rack meshing with the pinion, one of the brackets being formed with a guide channel in which the rack is mounted for movement, an operating lever fulcrumed on the car,

and an operative connection between the lever and the rack.

10

In testimony whereof, I affix my signature in presence of two witnesses.
